CAR DUMPER

Ernest W. Taylor and Melvin Pattison, Bay City,
Mich., assignors to Industrial Brownheist
Corporation, Bay City, Mich., a corporation of
Ohio

Application May 27, 1935, Serial No. 23,637

5 Claims. (Cl. 214—45)

This invention relates to car dumping apparatus for transferring coal or other friable material from one car to another or to a suitable receptacle.

5 One of the prime objects of the invention is to provide a car dumping mechanism for dumping or transferring material from one car into another and in such manner that the material is not dropped or broken, but is gently rolled and 10 discharged in a steady controlled stream so that an absolute minimum of "fines" and "slack" is produced.

Another object is to provide an intermediate material receiving means into which the material is dumped and which is actuated in proper sequence to smoothly and gently deposit the load in a transfer car or receptacle provided for receiving it.

15 A further object is to provide a car dumper construction of such character that the dumping operation occasions a minimum movement of the load, and consequently minimum amount of breakage.

A still further object is to provide simple and 20 practical means for transferring coal or other friable material from one car to another or to a suitable receptacle which is composed of few parts, all of substantial construction, and which is economical to assemble and operate.

25 With the above and other objects in view, the present invention consists in the combination and arrangement of parts, hereinafter more fully described, illustrated in the accompanying drawings, and particularly pointed out in the 30 appended claims, it being understood that changes may be made in the form, size, proportion, and minor details of construction, without departing from the spirit, or sacrificing any of the advantages of the invention.

35 In the drawings—

Fig. 1 is an end view of our improved car dumper mechanism, the solid lines showing the loaded car in position on the cradle, and the 40 hopper in position on the transfer car, the broken lines showing the position of the loaded car and transfer hopper when discharging into said hopper.

45 Fig. 2 is a side view showing the transfer car, hopper, and hopper rope system.

50 Fig. 3 is an enlarged, sectional, fragmentary view illustrating the car in the tilted position, the curtain lip swung down, and the hopper swinging into the transfer car, the travel being indicated by the arrows, the broken lines show-

ing the hopper in position for discharging into the transfer car.

5 Fig. 4 is a fragmentary sectional view showing the hopper in discharging position in the transfer car.

Fig. 5 is an enlarged fragmentary view illustrating one end of the hopper and one of the conveyers, the hopper being shown in section.

10 Fig. 6 is a fragmentary detail of the pivoted hopper, the broken lines showing the gates on the one side swung down to permit discharge of the load.

15 In the handling of coal or other friable material it is essential that the coal or material be controlled during the dumping operation so that it does not fall an appreciable distance, and so that large chunks do not gather momentum and crash into the coal stream or receiving receptacle and thus cause considerable breakage. To eliminate the forming of "fines" and "slack", which 20 command a lower price than does the unbroken material, it is necessary that the discharging or moving material flow and roll in a steady stream, and that the mechanism be so designed and operated that the coal does not "drop", but that 25 it gently flows and rolls from one receptacle or depository into another, and we have, therefore, designed simple, practical, and economical means for controlling the discharging and moving material so that it flows and rolls as above described, and with a minimum of movement and 30 breakage.

35 Referring now more particularly to the drawings in which we have shown one embodiment of our invention, the numeral 8 indicates the fabricated structure or tower of a car dumper of conventional design; this includes a cradle 9 provided with tracks 10 adapted to accommodate a conventional car 11 in which the material to be transferred is loaded. A side wall 12 forms a 40 part of the cradle, and the car 11 is shifted against said wall prior to the elevation and dumping thereof. Spaced apart clamps 13 are pivotally mounted on the cradle 9, and a curtain 14 is secured thereto and forms a closure for the open top of the car to confine the coal as the car 45 is tilted, a lip section 15 being formed on one edge of the curtain, all as shown and described in an application filed by Ernest W. Taylor under date of May 8, 1933, Serial No. 669,823, and when the car is tilted, this lip section swings outwardly (see Fig. 3 of the drawings) to permit the discharge of the coal, metering and confining the stream so that an even, controlled, and steady 50 flow is assured.

A transfer track 16 is provided directly adjacent the track 10, and transfer cars 17 operate thereon, these cars receiving the coal and transferring it to the desired location. The distance 5 from the inverted car to the transfer car is considerable, and it is not practical (due to the distance) to dump from one directly into the other, and we, therefore, provide an intermediate hopper member 18, which is pivotally mounted at 10 19 so that it can be swung upwardly to receive the coal from the tilted car and then swung down and into the transfer car for depositing the load therein.

The hopper 18 is formed as clearly shown in 15 Figs. 3, 4, and 6 of the drawings, being substantially V-shaped in cross section, and having an angled lip 20 on the inner edge thereof, gates 21 being provided on the lower end to permit the discharge of the load when the hopper is lowered 20 to position in the transfer car, and an additional gate 22 is provided on the inner edge to assist in this discharging operation when the hopper is swung upwardly, and as shown in Fig. 6.

Sheaves 23 are mounted on braces 24 which 25 are secured to the outer edge of the hopper to accommodate the rope system used for controlling the swinging thereof, and in a manner to be presently described.

A deflector plate 25 forms a part of the super- 30 structure and guides the discharging material into the hopper as the car is being tilted, and a machinery house 26 is provided on the frame, together with an operator's house 27 so that the 35 operator may be properly located to control the sequence of operation.

The equipment is designed to accommodate 40 and handle either one large capacity car or two small capacity cars simultaneously, and in order to accommodate the two small capacity cars, the 45 hopper is of greater length than the transfer car, and we, therefore, provide a conveyer 28 at each end of the hopper so that as the material is being discharged from the car, these conveyers can be driven, thus conveying the coal from the end sections to the hopped center sections 29 of the hopper, and which are provided with the gates 21 and 22 as above described; deflector plates 30 are also provided in each end of the hopper for deflecting the material onto the conveyers.

The mechanism for shifting, clamping, and 50 tilting the car, together with the cable arrangement for raising, etc. are of conventional design, and it is not deemed necessary to show or to describe them in detail, as this invention is directed to the means for transferring the material from the loaded car into the transfer car. The 55 hopper is controlled by means of the cables 31, anchored to the hangers 32, thence leading down and around the sheave 23, thence up and around the sheave 33, thence down and around the sheave 34, and up and over the sheave 35, and being wound on a winding drum 36 as usual, thence the cable leads back and over the sheave 37, and counterweights (not shown) are connected thereto.

In practice the loaded car is run onto the cradle and clamped in position; it is then carried upwardly in the dumper, and at a certain predetermined point is tilted, the hopper 18 being 70 swung upwardly and into position to receive the contents of the car; when the car is sufficiently tilted, the curtain lip 15 begins to swing down, and the coal begins to roll and flow in a steady stream into the hopper, the hopper then begins 75 to swing downwardly as it fills, until the entire

content of the car is deposited in said hopper, and where two small capacity cars are simultaneously handled, the conveyers 27 are operated to carry the coal from the end sections to the hopped center section. 5

The empty car now is swung back and is lowered, while the loaded hopper is swung down and into the transfer car, the gates 21 are then swung open so that the coal flows into the transfer car, the hopper is then again swung upwardly 10 so that the coal remains deposited in the transfer car—there has been a minimum movement of the coal, no drops or crushing, and the entire operation has been smooth and easy.

It will, of course, be understood that the 15 shape of the hopper and transfer car can be varied as desired, and that any other suitable receptacle may be substituted for the transfer car.

From the foregoing description it will be obvious that we have perfected a very simple, practical, substantial and economical material handling apparatus for handling coal and other friable materials. 20

What we claim is:

1. In a car dumper having a frame, the combination of a pivotally mounted V-shaped hopper arranged to receive the contents of a car, the upper edge of the inner wall section terminating in an outwardly flared lip, conveyers mounted in the ends of the hopper to convey the material 30 towards the center section thereof, and gates on the side walls of said hopper to permit the discharge of the material when the hopper has been swung to predetermined position. 25

2. In combination with a car dumper adapted 35 to carry a loaded car upwardly and at a certain elevation to tilt and dump the "load", a pivotally mounted V-shaped hopper arranged to receive the contents of the car, the upper section of the inner wall terminating in an outwardly flared 40 lip, means for metering the discharge of the "load" from the car onto the lip as the load is discharged, and gates on the side walls of the 45 hopper for discharging the "load" when the hopper has been swung to predetermined position.

3. In combination with a car dumper adapted 50 to elevate a loaded car and at a certain elevation to tilt and dump the contents thereof, a pivotally mounted, hopped member arranged 55 to receive the car contents and formed with a flared lip section on the upper section of the inner side wall, means for confining and metering the material as it flows from the car onto said flared lip section and into the hopper, and gates on the side walls of the hopper for releasing and depositing the load in a receptacle when the hopper has been swung to predetermined position. 60

4. In combination with a car dumper including 65 a tower, a cradle mounted therein and adapted to carry a loaded car upwardly and at a certain elevation to tilt and discharge the contents of the car, a pivotally mounted hopped member shaped member arranged to receive the contents 70 of the car, and formed with an offset relatively flat lip section on the upper edge of the inner side wall, a curtain mounted to limit and confine the load discharging from the tilted car onto said lip section and into the hopped member, and gates on the side walls of the hopped member to release the load when the hopped member is swung upwardly from its discharging position. 75

5. In combination with a car dumper of the 75

character described and including a cradle adapted to carry a loaded car upwardly and at a certain elevation to tilt and dump the contents thereof, a pivotally mounted hopper shaped member adapted to be swung upwardly and arranged to receive the load from the car, and formed with an offset relatively flat lip section on the upper edge of the inner side wall, means for con-

trolling the load discharge onto said lip section, means for actuating said hopper, and gates in the side walls of the hopper for releasing and discharging the contents into a suitable receptacle when the gates are opened and the hopper 5 is swung upwardly from its discharging position.
